UNITED STATES PATENT OFFICE.

GERMANN W. WEITMAN, OF CHICAGO, ILLINOIS, ASSIGNOR TO ECONOMY FUSE & MANUFACTURING CO., OF CHICAGO, ILLINOIS, A CORPORATION OF NEW YORK.

VARIABLE-PRESSURE HYDRAULIC PRESS.

Application filed May 4, 1922. Serial No. 558,485.

To all whom it may concern:

Be it known that I, GERMANN W. WEITMAN, a citizen of the United States, residing at Chicago, in the county of Cook and State of Illinois, have invented certain new and useful Improvements in Variable-Pressure Hydraulic Presses, of which the following is a specification.

The present invention relates to variable pressure hydraulic presses.

In many classes of work upon which a press is used, excessive pressures may have a ruinous effect upon said work. Various attempts have been made heretofore to modify the effective pressure of a hydraulic press, but in so far as applicant is aware, none of said schemes have proved entirely satisfactory.

A common type of hydraulic press has a reciprocating plunger mounted in a cylinder adapted to contain fluid under heavy pressure. Said cylinder may have guide members operatively associated therewith which provide bearings for said plunger. Fluid is admitted, under pressure, to said cylinder, the effective net pressure being proportional to the fluid pressure per unit area and the effective cross sectional area of the plunger. In service, the tremendous pressures to which the plunger is subjected sometimes cause the plunger to run askew, and the present invention has for one of its objects the provision of means for reducing the net effective pressure of a hydraulic press, which means will also be effective in minimizing the skewing effect referred to.

A further object of the present invention is the provision of a hydraulic press in which the effective pressure may be conveniently changed to suit varying operating conditions.

A further object is to provide a variable pressure hydraulic press in which the effective net pressure may be changed without modifying the pressure per unit area of the operating fluid.

A further object is to provide a hydraulic press having means for varying the effective net pressure thereof, which means will correspondingly vary the amount of liquid which need be pumped into the operating cylinder, whereby a reduction in the net effective pressure of the hydraulic press will involve a proportional reduction in the amount of power consumed.

A further object is to provide a variable pressure hydraulic press which will minimize the shocks incident to a system involving said press and which will be economical in operation.

Further objects will appear as the description proceeds.

Referring to the drawings—

Figure 1 is a top plan view of one embodiment of the present invention;

Figure 2 is a sectional view taken along the line 2—2 of Figure 1; and

Figure 3 represents a detail of construction.

The numeral 10 indicates a head member which may be mounted upon the four standards 11—11, being securely held thereon by means of the nuts 12—12. Said head member 10 has the cylinder portion 13, which may be cored out for the reception of fluid under pressure. Said head member is provided with a cylindrical hole 14 communicating with the interior of cylinder 15, which hole receives the plunger 15, adapted to have a running fit therein. A packing gland 16 may be provided, fastened to the head member 10 by means of bolts 17—17, which packing gland will hold packing 18 securely in place to prevent the escape of fluid between plunger 15 and head member 10.

The lower end of plunger 15 may be provided with a guide bar 19, which may have bearing engagement with the standards 11—11, and which may carry a die 20 for operation upon the material to be pressed. The cylinder 13 may be provided with a connection 21 for fluid under pressure. Valve mechanism, which need not be described herein, is provided for admitting fluid under pressure to the cylinder 13 through the connection 21 and for allowing the fluid to escape through said connection 21 when the plunger is to be moved back to the beginning of its operating stroke. Any preferred means may be provided for returning the plunger after it has performed its operating stroke.

At the end of the plunger 15, opposite to the guide bar 19, is a tail ram or extension bar 22 which may have a screw-threaded end 23 adapted to be mounted in a corresponding screw-threaded recess in the end of plunger 15. Said extension bar 22 when mounted in place in plunger 15 should be

perfectly rigid. Said extension bar 22, provides an added bearing for the reciprocating parts of the press, which bearing is distant from the guide bar 19, there is a 55
5 prevents the escape of fluid along said extension bar 22, said packing gland 24 having a screw-threaded portion adapted to be mounted in the upper wall of cylinder 13, a packing gland 24 being provided for preventing the escape of fluid along said extension bar 22, said packing gland 24 having a screw-threaded portion adapted to be mounted in the upper wall of cylinder 13
10 and having a packing flange 25 bolted thereto for holding a packing member 26 in close engagement with the extension bar 22.
15 According to the present invention, the extension bars 22 of different cross sectional dimensions may be provided for the purpose of varying the effective area of plunger 15. Two sizes of extension bars are shown in Figures 2 and 3. A set of extension bars 22 may be provided, which bars may have 20 screw-threaded end portions 23 of uniform size, whereby said extension bars 22 may be interchangeably mounted in the plunger 15. Different packing glands 24 will be provided to correspond to the various extension bars 22, all of said packing glands being designed to be interchangeably mounted in the top wall of cylinder 13.

25 The present invention presents the advantage that when the effective pressure of the hydraulic press is reduced, the amount of fluid which need be pumped into the operating cylinder 13 is correspondingly reduced. Inasmuch as the reduction in the amount of fluid pumped involves a corresponding reduction in the power consumed, it will be realized that, with the tremendous pressures involved, the saving is very considerable. The saving in power is accompanied by the saving involved in the shocks upon the machinery. In a plant using a number of hydraulic presses of the kind referred to, wherein a number of presses are operated from a central pumping point, a reduction in capacity of the presses is accompanied by an 40 increase in the number of presses which can be operated inasmuch as less fluid need be pumped to each press. The reduction in the total pressure to the value suitable for the work in the press is correspondingly easier 45 on dies.

50 Inasmuch as the engagement between the extension bar 22 and the packing gland 24

provides an added bearing for the reciprocating parts of the press, which bearing is distant from the guide bar 19, there is a 55 great reduction in the tendency for the plunger to run askew. When it is considered that any skewing effect of the plunger involves the danger of scoring the bearing surface thereof, the importance of the last 60 mentioned feature will be appreciated. Furthermore, as pointed out above, the amount of fluid necessary to be pumped is reduced when the effective pressure of the press is reduced, so that a reduction in effective 65 net pressure is accompanied by a proportional saving in power.

The illustrated embodiment of the present invention has been chosen merely for the purpose of describing the invention and 70 should not be considered in a limiting sense. Many modifications will occur to those skilled in the art. It is intended in this patent to cover all such modifications that fall within the scope of the invention as defined 75 by the appended claims.

I claim:

1. A hydraulic press having a head portion provided with a fluid receiving chamber, a plunger slidably mounted in said head member, a plurality of extension bars of varying cross sectional dimensions interchangeably applicable to said plunger for reducing the effective area thereof, and a plurality of packing glands interchangeably applicable to said enclosing means for packing said extension bars.

2. A hydraulic press comprising a reciprocating plunger, enclosing means therefor including a pressure cylinder, guide members, 90 said plunger having a guide bar rigid therewith operatively associated with said guide members, a plurality of extension bars of varying cross sectional dimensions interchangeably applicable to said plunger to 95 form a rigid connection therewith for reducing the effective area of said plunger, and a plurality of packing glands interchangeably applicable to said enclosing means for packing said extension bars.

100 Signed at Chicago, Illinois, this 22nd day of April, 1922.

GERMANN W. WEITMAN.
